CONTROL MEANS FOR MULTIPLE HYDRAULIC JACKS

Robert O. Bill, San Leandro, Calif.

Application January 10, 1949, Serial No. 70,132

5 Claims. (Cl. 60—97)

1

This invention relates to improvements in control means for hydraulic jacks, and particularly to hydraulic jacks used for elevating and lowering vehicle bodies, and provides positive means for elevating and lowering the various points on a vehicle body uniformly irrespective of the variations in load at the various points, and is particularly applicable to the truck, trailer, and semi-trailer elevating and lowering means disclosed in my copending applications Serial Numbers 10 34,963, filed June 24, 1948; 63,694, filed Dec. 6, 1948; 27,394 (now Patent No. 2,475,443 issued July 5, 1949), and 27,395, filed May 17, 1948; all of which disclose hydraulic means for elevating and lowering the beds or bodies of trucks, trailers, and semi-trailers; though the invention is not limited to this particular use, being applicable to any case where a plurality of jacks are to be simultaneously operated.

The invention also includes auxiliary means for varying the degree of rise or drop at the various points about the vehicle so that the vehicle body or bed can be tilted in any desired manner, diagonally, longitudinally, or transversely. With this auxiliary means any one of the jacks can be individually operated, or any two or more simultaneously and equally operated, making control of the battery of jacks universal.

As is well known, when a plurality of jacks is simultaneously operated, the jack with the least load will advance ahead of the heavier loaded ones, and with fairly great variations in loads the one with the least load is liable to operate alone if the fluid is supplied from a single source.

With my invention all jacks will operate equally irrespective of the variations in the loads on the various jacks, and if variations in the degree of operations of the various jacks is desired, the auxiliary means will permit of such variations irrespective of the variations in loads, while also permitting replenishment of any fluid which may have leaked from any jack, and also permit hand operation of the jacks either simultaneously or individually in case of failure of the main source of fluid under pressure.

The objects and advantages of the invention are as follows.

First, to provide a system for operation of a plurality of hydraulic jacks in which all jacks in the system will operate to the same degree irrespective of variations in the loads on the respective jacks.

Second, to provide a system as outlined in which operation of the jacks is carried out on the basis of displacement for each individual jack in the

system whereby all jacks will be advanced or retracted to the same degree irrespective of any variations in loads on the jacks.

Third, to provide a system as outlined in which the various jacks may be individually controlled and operated at will.

Fourth, to provide a system as outlined in which means is provided for individually replenishing the fluid supply in any jack at will.

Fifth, to provide a system as outlined with power operable means for operating the jacks, and with auxiliary manually operable means for operating the jacks in the event of failure of the power operable means.

In describing the invention reference will be had to the accompanying drawing, in which:

Fig. 1 is a schematic drawing of the entire system.

Fig. 2 is a section taken on line 2—2 of Fig. 1.

Fig. 3 is an enlarged vertical section through the manually-operable pump control for individual operation of the jacks and for replenishment of fluid in the individual jacks as occasion may require.

The invention is particularly applicable to vehicles and hydraulic elevating and lowering means for the beds or bodies thereof as disclosed in the aforementioned patent applications, in which a trailer, semi-trailer, or tractive front end of a

truck 10 has a hydraulic jack 11 having a cylinder 12 and a piston rod 13 which is coupled to the front end 14 of the trailer, semi-trailer, or truck body or bed 15, though not limited to a single jack for this end; and one or more jacks 16 and 17 for the respective rear wheels of the vehicle which are mounted on axles 18 and 19 fixed in hubs 20 and 21 which are integral with the pistons 22 and 23 which operate in the cylinders 24 and 25 and which in turn are supported by the wheel housings 26 or rear fenders 27 and by which the rearward end of the bed 15 is supported.

This system includes a supply of fluid 28, a pump 29 for delivering this fluid under pressure and which may be driven by any suitable means 45 such as by the vehicle engine or by a motor 30; the pump being preferably of a reversible type with the driving means also reversible, a master cylinder 31 having a piston 32 and piston rod 33 on the outer end of which is attached a plurality of piston rods 35, 36 and 37 equal in number to the number of hydraulic jacks to be operated, and each piston rod having a piston 38, 39, 40, with the pistons operating in their respective cylinders 41, 42 and 43, and the cylinders mounted in common mounting means such as the brackets 44 and

45 and which are mounted on some portion of the vehicle such as the drive end of the truck, front end of the trailer, or on the goose neck 46 of the semi-trailer.

The respective transfer cylinders 41, 42 and 43 have displacements equal to the displacements of the hydraulic jacks 11, 16 and 17 and are respectively connected to the working ends of the cylinders.

An auxiliary jack pump 47 is provided for manual operation of the jacks in the event of failure of the power for driving the pump 29, and when limited to that purpose may be a conventional multiple pump unit as is conventionally used for jacks; however, a pump is preferred which can be used for manual operation of the jacks, as also for replenishing the fluid supply in the jacks, and for individual control of the various jacks, and the control mechanism is illustrated in one concept in Fig. 3, in which the cylinder 48 has an intake valve 49, and a discharge passage 50 closed normally by a valve 51 against return of fluid to the supply.

Rotatable in the lower end of the base 52 is a shaft 53 on which is mounted a cam 54 having a low side 55 and a high side 56. Plungers 57 and 58 operate slidably through the housing with one end of each cooperating with the cam and the other ends cooperating with or cooperatively related to the respective valves, the other end of the plunger slightly clearing the valve when retracted as indicated at 59, and springs 60 urge the plungers to cooperate with the cam and retract from the valves; the pump intake being indicated at 61 and the discharge at 62.

For normal operation the discharge ends of the transfer cylinders 41, 42 and 43 are filled with oil, the pistons being fully retracted, and a supply of oil is provided in the tank 28. The bed or body of the vehicle is obviously resting on a surface.

To elevate the bed or body, the pump 29 is set in operation to pump oil from the storage tank 28 to the head end 63 of the master cylinder 31. This drives the piston 32 forward toward the other end of the cylinder, and, having direct connection with the piston rods 35, 36 and 37 through the head 34, the pistons 38, 39 and 40 are driven forward, forcing the oil 64 in these cylinders through the respective conduits 65, 66 and 67 to the respective jacks 17, 16 and 11, elevating the bed 15 equally at all points of suspension by the jacks, and to a height proportionate to the degree of operation of the pump 29 being terminated when the desired elevation of the bed is attained.

When the bed is to be lowered, the pump 29 can be reversed, or the valve 68 may be opened to allow the oil in the head end 63 of the cylinder to drain back to the supply tank under the urging of the load on the jacks. When the bed has reached the desired level, the valve is closed, holding the bed at that level.

In the event of power failure so that the pump 29 cannot be operated, the pump 47 is manually operated, delivering fluid from the supply 28 through the pipe 69, thence through the pump 47, and lines 70, 71 and 72 to the conduits 65, 66 and 67 and thence to the jacks, the transfer cylinders being filled with oil and the pistons retracted so that only the jacks need be filled to cause the raising of the bed. This pump is operated by the handle 73 and controlled by the knobs 74, 75 and 76, the pump shown being the conventional 3-cylinder hydraulic jack pump.

With the arrangement shown in Fig. 3, complete control of the several jacks, collectively or

individually, is possible. Normally, the knobs 74, 75 and 76 (Fig. 1) are set so that the low side 55 of the cam is up and both plungers 57 and 58 rest on this low side, freeing the valves, so that fluid is taken from the tank 28 through the line 69 thence through the several intake ports 61, drawn past the valves 49, when the pump pistons are drawn upward, and discharging through the passages 50 past the valves 51 to the respective conduits 65, 66 and 67, this being normal operation.

In case one of the jacks should leak part of its oil, say the jack 11, the knobs 74 and 76 are adjusted to move their associated cams to the position shown in Fig. 3, or mid-position, while the knob 75 is left in its normal position with both valves operating. In this case, the two pumps 78 and 79 will merely idle, drawing oil from the supply tank 28 and then returning it, while the other pump 77 will pump oil to the jack 11.

When the bed is to be lowered, it is merely necessary to turn the knobs to their farthest clockwise position, in which case both plungers 57 and 58 will rest on the high side 56 of the respective cams, keeping both valves open. Thus it is possible with this arrangement to selectively supply additional oil to the respective jacks, selectively drain from any or all jacks, pump to selected jacks while draining from others, or pump equally to all jacks for emergency operation in the event of power failure, making operation selective or universal at will.

I claim:

1. Operating means for a plurality of hydraulic 35 jacks comprising a master cylinder and a supply of fluid under pressure therefor and control means for said supply; transfer cylinders equal in number to the number of jacks to be operated and having displacements equal to that of the jacks 40 operated thereby, and a supply of fluid for each cylinder and equal to its displacement, communication between each cylinder and its jack; a master piston for said master cylinder and a transfer piston for each transfer cylinder and operative connections between said master piston and said transfer cylinders for equal operation of the transfer pistons by the master piston; a plurality of pumps equal in number to the number of hydraulic jacks, and manual operating 50 means for simultaneously and equally operating all of said plurality of pumps, with the respective pumps having communication between said supply of fluid and the respective jacks, and said plurality of pumps each including control means 55 individually operable for controlling idling in, drainage from, and delivery of fluid to, the respective jacks at will while all of said plurality of pumps are simultaneously operated.

2. Means for simultaneously operating a plurality of hydraulic jacks to the same degree irrespective of variations in loads on the jacks, comprising; a transfer cylinder for each jack and having a communicating connection therewith and having a supply of liquid equal to the displacement of the jack plus the internal volume of the connection; a piston for each transfer cylinder with the strokes of all pistons being equal; and means for simultaneously operating all of the pistons simultaneously and to the same degree; whereby operation of the said pistons in opposite directions will simultaneously operate all jacks in equal degrees of movement in respective directions; a pump for each jack and having a communicating connection therewith; means for 70 manually operating all of said pumps simultane-

ously and to the same degree; each of said pumps including valve control means adjustable to three positions, in one of which the pump idles, in another of which liquid will drain through the pump from the jack, and in the other of which the pump delivers liquid under pressure to the jack, and a supply of liquid for said pumps.

3. Means for simultaneously operating a plurality of hydraulic jacks to the same degree irrespective of variations in loads on the jacks, comprising; a transfer cylinder for each jack and having a communicating connection therewith and having a supply of liquid equal to the displacement of the jack plus the internal volume of the connection; a piston for each transfer cylinder with the strokes of all pistons being equal; and means for simultaneously operating all of the pistons simultaneously and to the same degree; whereby operation of the said pistons in opposite directions will simultaneously operate all jacks in equal degrees of movement in respective directions; a pump for each jack and having a communicating connection therewith; means for manually operating all of said pumps simultaneously and to the same degree; each of said pumps including valve control means adjustable to three positions, in one of which the pump idles, in another of which liquid will drain through the pump from the jack, and in the other of which the pump delivers liquid under pressure to the jack, and a supply of liquid for said pumps; said means for simultaneously operating all of said transfer cylinders comprising; a master cylinder having a piston terminating in a head; a piston for each transfer cylinder and fixed to said head; a supply of fluid for said master cylinder, and a reversible pump for delivering liquid to and for withdrawing liquid from said master cylinder, and means for operating said reversible pump.

4. Means for simultaneously operating a plurality of hydraulic jacks to the same degree irrespective of variations in loads on the jacks, comprising; a transfer cylinder for each jack and having a communicating connection therewith and having a supply of liquid equal to the displacement of the jack plus the internal volume of the connection; a piston for each transfer cylinder with the strokes of all pistons being equal; and means for simultaneously operating all of the pistons simultaneously and to the same degree; whereby operation of the said pistons in opposite directions will simultaneously operate all jacks in equal degrees of movement in respective directions; a plurality of control pumps equal in number to the number of hydraulic jacks and means for simultaneously operating said control pumps to an equal degree, and a supply of liquid for said control pumps; a valve system for each pump and control means therefor manually adjustable at will to one position in which liquid is delivered to its jack, in another of which the pump idles while retaining the contained liquid in its jack, and in the other of which the liquid in the jack is released for pas-

sage through the pump to said supply, irrespective of the adjustments of the other control pumps, whereby the control pumps may be used for simultaneously or individually operating the jacks in either direction, at will, irrespective of operation of said means for simultaneously operating all of the pistons.

5. Means for simultaneously operating a plurality of hydraulic jacks to the same degree irrespective of variations in loads on the jacks, comprising; a transfer cylinder for each jack and having a communicating connection therewith and having a supply of liquid equal to the displacement of the jack plus the internal volume of the connection; a piston for each transfer cylinder with the strokes of all pistons being equal; and means for simultaneously operating all of the pistons simultaneously and to the same degree; whereby operation of the said pistons in opposite directions will simultaneously operate all jacks in equal degrees of movement in respective directions; said means for simultaneously operating all of said transfer cylinders comprising; a master cylinder having a piston terminating in a head; a piston for each transfer cylinder and fixed to said head; a supply of fluid for said master cylinder, and a reversible pump for delivering liquid to and for withdrawing liquid from said master cylinder, and means for operating said reversible pump; a plurality of control pumps equal in number to the number of hydraulic jacks and means for simultaneously operating said control pumps to an equal degree, and a supply of liquid for said control pumps; a valve system for each pump and control means therefor manually adjustable at will to one position in which liquid is delivered to its jack, in another of which the pump idles while retaining the contained liquid in its jack, and in the other of which the liquid in the jack is released for passage through the pump to said supply, irrespective of the adjustments of the other control pumps, whereby the control pumps may be used for simultaneously or individually operating the jacks in either direction, at will, irrespective of operation of said means for simultaneously operating all of the pistons.
